CLAIM

The ornamental design for a shipping and dispensing construct, as shown and described.

DESCRIPTION

FIG. 1 is a front perspective view of a shipping and dispensing construct showing my new design according to a first exemplary embodiment.

FIG. 2 is a bottom perspective view of the shipping and dispensing construct of FIG. 1.

FIG. 3 is a perspective view of the shipping and dispensing construct of FIG. 1 showing the handle thereof in an extending position.

FIG. 4 is a front elevation view of the shipping and dispensing construct of FIG. 1.

FIG. 5 is a right elevation view of the shipping and dispensing construct of FIG. 1.

FIG. 6 is a rear elevation view of the shipping and dispensing construct of FIG. 1.

FIG. 7 is a left elevation view of the shipping and dispensing construct of FIG. 1.

FIG. 8 is a top plan view of the shipping and dispensing construct of FIG. 1.

FIG. 9 is a bottom plan view of the shipping and dispensing construct of FIG. 1.

FIG. 10 is a plan view of the shipping and dispensing construct of FIG. 1 shown in an unfolded configuration.

FIG. 11 is a front perspective view of a shipping and dispensing construct showing my new design according to a second exemplary embodiment.

FIG. 12 is a bottom perspective view of the shipping and dispensing construct of FIG. 11.

FIG. 13 is a perspective view of the shipping and dispensing construct of FIG. 11 showing the handle thereof in an extending position.

FIG. 14 is a front elevation view of the shipping and dispensing construct of FIG. 11.

FIG. 15 is a right elevation view of the shipping and dispensing construct of FIG. 11.

FIG. 16 is a rear elevation view of the shipping and dispensing construct of FIG. 11.

FIG. 17 is a left elevation view of the shipping and dispensing construct of FIG. 11.

FIG. 18 is a top plan view of the shipping and dispensing construct of FIG. 11.

FIG. 19 is a bottom plan view of the shipping and dispensing construct of FIG. 11; and,

FIG. 20 is a plan view of the shipping and dispensing construct of FIG. 11 shown in an unfolded configuration.

All evenly-spaced broken lines depict environmental subject matter and do not form part of the claimed design.
